United States Patent Office.

GEORGE T. CHATTAWAY, OF BROOKLYN, E. D., AND JOHN DICKINSON, OF NEW YORK, N. Y., ASSIGNEES TO GEORGE T. CHATTAWAY.

Letters Patent No. 98,028, dated December 21, 1869.

IMPROVEMENT IN GRINDING-MACHINES.

The Schedule referred to in these Letters Patent and making part of the same.

To all whom it may concern:

Be it known that we, GEORGE T. CHATTAWAY, of Brooklyn, E. D., in the county of Kings, and State of New York, and JOHN DICKINSON, of the city and State of New York, have invented and made an Improvement in Grinding-Apparatus applicable to sewing-machines; and the following is declared to be a correct description of the same.

Our invention is made with special reference to the grinding of scissors with uniformity in the angle of the cutting-edge, and that by a portable apparatus, adapted to use upon a sewing-machine, at the place where the bobbin-winder is usually applied, so as to be driven by the belt that leads to the main shaft and fly-wheel.

We employ a swinging rest, upon which the scissors-blade is to lie, so as to adjust the angle at which the cutting-edge is to be ground, by moving the said rest by means of screws, and this rest is upon a movable bed, and combined with a revolving grinding-wheel.

Figure 1 is a vertical section, and

Figure 2 is a plan of the said grinding-apparatus.

In the drawing—

a represents a bed, with a flange, *b*, below, that serves to steady the bed in the position at which it may be placed upon the sewing-machine table. A clamp may be applied at this point if desired.

The grinding-wheel *c* is mounted upon the shaft *d*, set in bearings *e*, and driven by a belt to the pulley *f*.

The rest *g* is mounted upon trunnions *i*, in the bearings *h*, that are held by screws *k*, and are adjustable nearer to or further from the grinding-wheel *c*.

The screws *l* and *m* serve to hold the rest *g* at any angle to the radial or tangent lines of the wheel *c*, at the point where the grinding takes place, so that when the blade of a pair of scissors is laid upon the said rest, the cutting-edge can be ground to any desired angle to the face of the blade, by inexperienced persons, such as ladies, and thus scissors can be sharpened with ease and accuracy.

We claim, as our invention—

The rest *g*, set upon trunnions in the movable bearings *h*, and adjusted by the screws *l* *m*, in combination with the grinding-wheel *c* and bed *a*, as and for the purposes specified.

Dated November 5, A. D. 1869.

GEO. T. CHATTAWAY.

JOHN DICKINSON.
